UNITED STATES PATENT OFFICE.

LOLIE McCRAKEN, OF SANTA ANA, CALIFORNIA.

EXPANSION PLUG FOR ELECTRIC CONNECTIONS.

Application filed July 13, 1920. Serial No. 395,911.

To all whom it may concern:

Be it known that I, LOLIE McCRAKEN, a citizen of the United States, residing at Santa Ana, in the county of Orange and 5 State of California, have invented new and useful Improvements in Expansion Plugs for Electric Connections, of which the following is a specification.

This invention relates to expansion plugs 10 for electric connections and has for its prime object the provision of a plug for use in connection with extension cords, and the like, which may be easily and quickly attached to or detached from, an electric light 15 socket, without the necessity of screwing or unscrewing it, as has heretofore been the common practice.

With my improved plug, as herein shown and described, not only is the screwing and 20 unscrewing operation avoided, but also the entangling of the depending cord resulting from such operation, is obviated.

The details of my invention, and its function, will be fully set forth in the following 25 specification, reference being made to the accompanying drawings forming a part thereof, and in which:

Fig. 1 is an elevation of the plug showing a portion in section.

Fig. 2 is similar view taken at a right angle to the view shown in Fig. 1, and showing a portion of the casing broken away.

Fig. 3 is a fragmentary transverse sectional elevation taken on the line 3—3 of Fig. 1.

Fig. 4 is a transverse sectional elevation, showing the plug as applied to a standard electric light socket, parts being shown in section to display the securing means, the sectional parts taken as indicated by line 40 4—4 of Fig. 6.

Fig. 5 is a vertical transverse section taken on line 5—5 of Fig. 6.

Fig. 6 is a top plan view.

Fig. 7 is a transverse section taken as 45 indicated by the line 7—7 of Fig. 5.

Referring now to the drawings the numeral 10 designates a casing, constructed of metal, or any suitable material, in which a semi-cylindrical core 11 is rigidly secured 50 by means of screws 12, or in any other appropriate manner.

A lower hemispherical cap 13, terminating in a cylindrical portion 14, is secured to the lower end of the casing 10, by means of 55 screws 15, and has a lower depending tubular portion 16, formed integral therewith,

through which the insulated wires 17 and 18 pass, and which is only added to give a finished and neat appearance to my device.

The core 11 is constructed of any suitable 60 non-conductive material such as vulcanite, fibre or porcelain, and is preferably formed of two halves 19 and 20, although this method of construction may be altered without departure from the spirit of my invention. The members 19 and 20, of the core 11 are cut off as at 21 and 22, respectively, to form a flat face 23, to which a resilient 65 plate 24 is secured, adjacent its lower edge, by means of small bolts 25, extending 70 through holes 26 in the members 19 and 20. It may be here noted, that the halves 19 and 20, of the core 11, are securely held together by the casing 10, and the plate 24, in addition to its normal function, serves to 75 further secure these parts together.

The plate 24 may be constructed of any 80 light resilient electro-conductive material, and has a screw-threaded or corrugated portion 27, extending downwardly from its top, to conform to the size and pitch of the internal screw-threads 28 of the shell 29 in a standard electric light socket 30. Plate 24 is adapted to normally rest against the 85 flat face 23, throughout its length.

The core 11 is reduced, as at 31, for a short distance extending downwardly from its top to receive a screw-threaded metal split collar 32, likewise conforming to the internal screw threads 28 of the shell 29, and 90 forming the usual means of removably attaching the plug to the socket. While I have here shown the collar 32 to be separate and constructed of metal, it can be seen that suitable threads may be easily formed integral with the core. When the collar 32 is used it may be applied by cement or other well known means.

The members 19 and 20 of the core 11 are 100 recessed as at 33 to form a seat for a vertically extending rod 34, which is adapted to be supported in the position shown in Fig. 3 by means of a collar 35, resting on outwardly projecting ledges 36 on the portions 19 and 20. An actuating arm 37 extends outwardly from the lower end of rod 34, at about right angles thereto, through a slot 38, in the casing 10, and has a handle 39 secured thereon. The upper end of the rod 34 is bent to form a contact arm 40, normally 105 resting in a recess 41 formed in the portions 19 and 20. Arm 40 is adapted to contact 110

with the rear face of the plate 24 to spring it outwardly and effect its engagement with the shell 29 of the socket 30, in the manner hereinafter set forth.

5 Electrical energy is supplied to the plug in the following manner: The insulated wire 17 is secured to a plate 42, which in turn is secured to the portion 19 of the core 11 by means of bolt 43; the lower portion 16 of the core 11 being recessed as at 44 to receive such fastening means. The cap screw 45 by which the wire 17 is secured to the plate 42, also receives a wire or rod 46 extending upwardly through an aperture 47 15 formed in the halves 19 and 20 of the core 11, and which connects at its upper end to a spring contact 48 mounted on the top of said core. The spring contact 48 may be secured to the core in any suitable manner, and is here 20 shown as being attached to a metal plate 49, set in a recess 50 in the portion 19 of the core 11, by means of a cap screw 51. The wire 46 may be either directly connected to the spring contact 48, as shown in Fig. 5, 25 or may be secured to the metal plate 50. In a similar manner the other wire 18 is secured to a plate 52 which is fixed to the portion 20 of the plug 11 by means of a bolt 53 the bolt being set in a recess 54. The cap 30 screw 55 by which the end of the wire 18 is secured to the plate 52 also receives one end of a wire 56 which extends upwardly through the aperture 47, and is adapted to extend through an aperture 57 and contact with the collar 32. Thus it will be seen that electrical contact is made by the plug when inserted in the socket 30, through the contact 48 contacting with the contact 60 of the socket 30; and the other contact being made 40 with the shell 29 through the collar 32, in the usual manner.

In the operation of my device the various parts are normally in the position shown in Fig. 1, the member 24 resting against the face 23 of the core 11, and in which position the plug is ready to be inserted in the socket 30. After inserting the upper end in the socket 30, the handle 39 is moved to the right of the position shown in Figs. 1, 2, 50 and 3, swinging the arms 40 outwardly and in contact with the rear face of plate 24, forcing the latter outwardly and into engagement with the screw threads 28 of the shell 29, which operation wedges the collar 32 into a similar engagement around the opposite side of the socket, as clearly 55 illustrated in Fig. 4.

While I have here shown and described my

device in its preferred form, it is understood that I reserve the right to make any modifications in the structure, as properly come within the scope of the appended claims.

Having described my invention, I claim:

1. An expansion plug for electric connections comprising a core of non-conductive material formed in two pieces, each piece having a flat face on one side, screw threaded engaging means on the upper end of the core, extending around its arcuate side to engage the inner screw threads of a socket, a plate secured to and normally resting against and uniting the flat faces of the plug and adapted to be sprung outwardly at its top, and having a corrugated portion at its top corresponding with the said screw threads 75 on the core, a rod revolvably mounted on the core back of said plate, having an arm on its upper end normally resting in a recess in the core and adapted to be swung outwardly and engage the rear face of the plate 80 to spring it outwardly to and wedge the said screw threads into engagement with the inner screw threads of a socket, a contact plate on the top of the core, electrical conductors connecting with the said screw threaded 85 portion and said contact plate and a casing for the lower end of the core.

2. An expansion plug for electric connections comprising a two-piece core, a contact plate secured to both pieces of said core and 90 uniting the same at one end and adapted to be sprung outwardly at its other end, said core and plate being arranged to be received in a socket, and a rod revolvably mounted on the core back of said plate and adapted to 95 engage the latter to spring it outwardly and wedge the plate in said socket.

3. An expansion plug for electric connections comprising a two-piece core and each piece having a flat surface, a contact plate secured to both of said flat surfaces of the core and uniting the same at one end and adapted to be sprung outwardly at its other end, said core and plate being arranged to be received in a socket, and a rod revolvably mounted 100 on the flat surface of the core back of said plate, said rod having an arm at its upper end normally resting in a recess in the core and adapted to be swung outwardly and engage the rear face of the plate to spring 105 it outwardly and wedge the plate in said socket.

In testimony whereof I have signed my name to this specification.

LOLIE McCACKEN.
